UNITED STATES PATENT OFFICE.

WALLACE E. WARD, OF NEW YORK, N. Y., ASSIGNOR TO ARTHUR H. INGLE,
OF ROCHESTER, NEW YORK.

LATHE HEADSTOCK AND FEED MECHANISM WITH RAPID TRAVERSE.

Application filed May 16, 1919, Serial No. 297,587. Renewed October 20, 1922. Serial No. 595,865.

To all whom it may concern:

Be it known that I, WALLACE E. WARD, a citizen of the United States, and resident of New York, county of New York, State of New York, have invented an Improvement in Lathe Headstock and Feed Mechanism with Rapid Traverse, of which the following description, in connection with the accompanying drawings, is a specification, like characters on the drawings representing like parts in each of the several views.

This invention relates to lathe mechanism and more particularly to improvements in the gear connections to the feed shaft for the tool carriage whereby a requisite range of feed changes may be quickly and easily effected, and in conjunction therewith a rapid traverse connection to the feed shaft is provided that is actuated directly from a high speed shaft of the machine that is preferably the prime drive shaft. One important object of the invention is to provide a rapid traverse connection to the feed shaft that is connectible therewith alternatively with the feed gear train, but is actuated entirely apart from and independent of the feed gear train. In accordance with my invention the rapid traverse transmission to the feed shaft is preferably derived direct from the prime drive shaft of the machine while the feed transmission is preferably derived from the spindle through suitable back gearing. The foregoing and other objects and advantages of the invention will more fully appear from the following detailed description, and the distinctive features of novelty will be pointed out in the appended claims.

Referring to the drawings:

Fig. 1 is a side elevation of a lathe embodying the invention;

Fig. 2 is an end view thereof;

Fig. 3 is a diagrammatic section illustrating the operating connections to the rapid traverse and to the feed transmission;

Fig. 4 is a partial section showing particularly the feed change mechanism and the connection to the rapid traverse; and

Fig. 5 is a detail cross section showing the interconnection of certain clutch elements.

10 indicates the lathe bed with a tool carriage 11 fitted for movement therealong under the actuation of a feed shaft 12 which may be connected as usual to not only feed the carriage 11 but also to effect a cross feed

(not shown) of the tool slide thereon. 13 indicates the headstock housing in which is journaled the headstock spindle 14 equipped with a usual center 15 and with a face plate 16 fitted to the end thereof. Also journaled in the headstock housing in parallelism with the spindle is a high speed shaft 17 which has fixed on a projecting end thereof a driving pulley 18, this shaft being for purposes of the present description the prime drive shaft of the machine deriving its power from any suitable source such as an electric motor 19 mounted on the top of the headstock housing. The shaft 17 has slidably keyed thereon in spaced apart relation a pair of pinion blocks 19, 20 formed with pinions of diverse sizes adapted to be selectively engaged with a series of spaced apart gears 21 fixedly carried on a sleeve 21^a loosely journaled on a shaft 22. The sleeve 21^a is equipped at its inner end with a clutch face 23 which is engageable by a co-operative clutch face on a clutch sleeve 24 slidably keyed at the inner end of a shaft 25 journaled in the housing, and having fixed to its other end a pinion 26 in mesh with an internal gear 27 of the face plate 16. The shaft 25 has loosely fitted adjacent the inner end thereof a gear 28 with a clutch face at the inner side thereof adapted to be engaged by a clutch face on the outer end of the clutch sleeve 24 upon a shifting of the same to the right as seen in Fig. 3. The gear 28 is engaged by a pinion 29 fixed on a shaft 30 journaled in the housing. This shaft has a gear 31 loosely journaled thereon in mesh with the smallest one of the set of gears 21 and also has slidably keyed thereon another gear 32 meshing in one position with a larger one of the gears 21. The gears 31, 32 are equipped with hub sleeves extending towards each other with opposite clutch faces 31^a, 32^a respectively adapted to be brought into engagement as the gear 32 is shifted to the right, this shifting disconnecting it from the gear 21. This arrangement permits a range of twelve speed changes from the shaft 17 to the spindle as will be readily understood but need not be further elaborated herein, since this construction specifically, forms no part of the present invention. A reduced inner end 12^a of the feed shaft 12 is journaled as indicated at 33 in a bearing associated with the feed box housing 34 and the extremity of this shaft end extending 110

2

within said housing has fixed thereon a pinion 35. This pinion is in mesh with a pinion 36 mounted on a countershaft 37 journaled at the base of the feed box housing this 5 pinion being normally loose on said shaft but adapted to be clutched thereto by a suitable clutch device 38. The shaft 37 has its outer end mounted in an extended sleeve bearing 39 of the feed box housing, and its 10 projecting extremity has fixed thereon a sprocket wheel 40 which is engaged by a sprocket chain 41 which is driven by a sprocket wheel 42 mounted on a stub shaft 43. The sprocket wheel 42 has rigid there- 15 with another sprocket wheel 44 which is driven by a sprocket chain 45 from a sprocket wheel 46 fixed on the prime drive shaft 17. Through this connection the feed shaft may be rapid traversed by movement 20 derived directly from the prime drive shaft through the described sprocket chains and shaft 37. Journaled in the feed box housing in endwise alinement with the feed shaft extension 12^a and abutting thereagainst is a 25 shaft 47 having loosely mounted thereon spaced apart gears 48, 49 of diverse sizes and equipped with clutch faces 48^a, 49^a on the sides thereof facing each other. These clutch faces are adapted to be selectively en- 30 gaged by a clutch sleeve 50 slidably keyed on the shaft 47. The shaft 47 has also slidably keyed on the inner end thereof another clutch sleeve 51 which in one position is adapted to engage with a clutch face 35^a 35 formed on the gear 35. The gears 48, 49 are in mesh respectively with diverse sized gears 52^a, 52^b of a change gear bank 52 all the gears of which are keyed on a shaft 53 journaled in the feed box. The several gears of 40 the gear bank 52 are selectively engageable by a pinion 54 mounted on a radius arm 55 45 swingingly mounted on a shaft 56 journaled in the feed box, the pinion 54 being constantly driven in its different angular positions by gear connections 57 from said shaft. The shaft 56 has slidably keyed on a project- 50 ing end portion 58 thereof a pair of gears 59, 60 of diverse sizes both carried with a spacing sleeve 61 for movement together and having an outwardly projecting flange head 62 for convenient actuation. These gears are adapted to be shifted so that either the smaller gear 59 may be engaged with a larger gear 63, or the larger gear 60 may 55 be brought into engagement with a smaller gear 64 of a gear pair journaled on a stub shaft 65 of the headstock housing, these gears being driven from a gear 66 keyed on a shaft 67 journaled in the headstock housing 60 and actuated by a gear 68 slidably keyed thereon. The gear 68 is driven in one direction when it is positioned so as to engage with a gear 69 fixed on the spindle 14 while when slid to its other position it is driven 65 in the opposite direction by an intermediate gear 70 which is driven from a gear 71 also fixed on the headstock spindle, this accomplishing a reversal of the direction of feed movement as required. It is essential that both the clutches 38, 51 be not engaged at the 70 same time as this would result in an interlock of the rapid traverse and the feed gear train. I therefore connect these clutches by means of a rocker arm 72 fixed at an intermediate point to a shaft 73 journaled in the 75 housing and having its opposite ends engaged with the shipper grooves 38^a, 51^a of the respective clutch sleeves, this shaft having a projecting outer end thereof equipped with a suitable handle 73^a. Thus as either 80 clutch is shifted into operative position it is insured that the other clutch will be disengaged at the same time. The clutch sleeve 50 is engaged by a suitable shipper (not shown) mounted on a rock shaft 50^a and actuated by 85 an external handle 50^b at the front of the feed box. The radius arm 55 has a project- 90 ing handle 55^a at the front of the feed box co-operative with a locking plate 55^b as is usual in this type of device. With the de- 95 scribed system of connections, the feed shaft may thus derive rapid traverse movement direct from the prime drive shaft without interfering with or disarranging any setting of the feeds that may have been made, this being accomplished by merely shifting the 100 clutch lever 73^a so as to engage the clutch 38 with the gear 36, which operation at the same time shifts out the clutch sleeve 51 from engagement with the gear 35. When 105 the feeds are to be connected for operation the lever 73^a is shifted in the other direction to engage the shaft 47 through the clutch 51 with the feed shaft. The feed changes ac- 110 complished by the gear bank 52 which consists as illustratively shown, of eight pinions, is multiplied by two through the selective engagement of the shaft 47 with either the gear 48 or the gear 49 according to the ad- 115 justment of the clutch sleeve 50 and the sixteen feed changes thus attained are again multiplied by two according to the shifting of the gear pair 59, 60 on the shaft extension 58 to drive either the smaller gear 59 from the larger gear 63 or the larger gear 60 from 120 the smaller gear 64. The direction of feed movement thus effected may be reversed by the shifting of the gears 60, 68 along the shaft 67 to cause it to mesh with either the spindle gear 69 or the intermediate 70. I 125 am aware that the invention may be embodied in other specific forms without departing from the spirit or essential attributes thereof, and I therefore desire the present embodiment to be considered in all 125 respects as illustrative and not restrictive, reference being had to the appended claims rather than to the foregoing description to indicate the scope of the invention.

Having described my invention, what I 130

claim as new and desire to secure by Letters Patent is:

1. Lathe mechanism comprising a spindle, a high speed drive shaft, a feed shaft, 5 means for connecting said high speed drive shaft directly with said feed shaft for rapid traverse, including a countershaft mounted in parallelism with said feed shaft and also with said high speed drive shaft 10 and with said spindle, there being a disconnecting clutch between said high speed drive shaft and feed shaft adapted to disengage the same in either direction of movement, and change feed gearing connections from said spindle to said feed shaft, also including a disconnecting clutch. 15
  2. Lathe mechanism, comprising a spindle, a high speed drive shaft, a feed shaft, means for connecting said high speed drive shaft directly with said feed shaft for rapid traversing including a disconnecting clutch, a change feed gear train to said feed shaft including a disconnecting clutch, and means associated with said disconnecting clutches for preventing the connection of more than one of them at the same time on either direction of movement. 20
  3. Lathe mechanism, comprising a spindle, a high speed drive shaft, a feed shaft, 30 direct connections from said high speed drive shaft to said feed shaft for rapid traversing the same including an element for breaking said connection at will, a change feed gear train from said spindle to the feed shaft including an element for 35 breaking the connection at will, and means preventing the engagement of said rapid traverse connection and said feed connection with the feed shaft at the same time 40 on either direction of movement.
  4. Lathe mechanism, comprising a high speed drive shaft, a work spindle, a feed shaft, a countershaft driven direct from said drive shaft having a gear loose thereon meshing with a gear fixed on the feed shaft, a clutch for engaging said countershaft with the gear thereon, a change feed gear connection from the spindle to said feed shaft including a countershaft mounted 45 in axial alignment with the feed shaft, a clutch for connecting said axially aligned shaft with the feed shaft, and means for preventing the engagement of both of said clutches at the same time. 50
  5. Lathe mechanism, comprising a spin- 55
- dle, a high speed drive shaft, change speed gearing from said drive shaft to said spindle, a feed shaft for operating the work carriage, change feed gearing from said spindle to said feed shaft, and a rapid traverse connection direct from said high speed drive shaft to said feed shaft and engageable therewith selectively with said feed change gearing, said rapid traverse connection and said change feed gearing from the spindle to the feed shaft being equipped with interconnected means whereby when one thereof is engaged with the feed shaft the other is wholly disconnected therefrom. 60
6. Lathe mechanism, comprising a high speed drive shaft, a work spindle, change speed gearing for connecting said drive shaft to said spindle, a feed shaft for operating the work carriage, change feed gearing from said spindle to said feed shaft 65 including a disconnecting clutch, and a countershaft mounted in parallelism with said feed shaft and connected to be driven directly from said high speed drive shaft, said countershaft equipped with means for engaging the same in driving relation to said feed shaft selectively with said change feed gearing, and of a character to be wholly disengaged from the feed shaft when the change feed gearing is engaged therewith. 70
7. Lathe mechanism, comprising a high speed drive shaft, a work spindle, change speed gearing connecting said drive shaft with said spindle, a feed shaft for operating the work carriage, change feed gearing connecting said spindle with said feed shaft for operating the work carriage, change feed gearing connecting said spindle with said feed shaft including a shaft mounted 75 in axial alignment with said feed shaft and having a clutch for engaging the same therewith, a counter shaft for imparting rapid traverse movement mounted in parallelism with said feed shaft and connected to be driven directly from said high speed 80 drive shaft, and means for engaging said countershaft in driven relation to said feed shaft connected with the first named clutch so that said feed connection and said rapid traverse connection may not be both engaged at the same time. 85
- In testimony whereof I have signed my name to this specification. 90

WALLACE E. WARD.
